UNITED STATES PATENT OFFICE.

LAWRENCE LOTTIER, OF RICHMOND, VIRGINIA.

MACHINE FOR DRYING TOBACCO.

SPECIFICATION forming part of Letters Patent No. 257,031, dated April 25, 1882.

Application filed March 30, 1880. (No model.)

To all whom it may concern:

Be it known that I, LAWRENCE LOTTIER, of Richmond, in the county of Henrico and State of Virginia, have invented a new and 5 useful Improvement in Machines for Drying Tobacco; and I do hereby declare that the following is a full and exact description of the same, reference being had to the accompanying drawings, and to the letters of reference 10 marked thereon.

The object of my invention is to provide a simple and cheap machine for evaporating the surplus moisture out of the tobacco after it has passed through the sweetening solution, 15 or at any stage of a process requiring the water to be evaporated, and at the same time the tobacco-leaves to be left in a soft and pliable condition for manipulation. To accomplish these ends it has heretofore been the practice 20 to dry the tobacco in the sun—a slow and troublesome process, depending entirely upon bright sunlight for success—or in tightly-closed dry-rooms or air-tight boxes by means of direct or indirectly radiated heat, which prevents 25 the vapors from escaping, thereby causing the leaf to bake and darken, requiring it to be moistened by steam, which still further darkens it and injures its flavor.

In my invention the results sought for are 30 obtained by spreading the tobacco upon a screen of perforated metal, wire-gauze, netting, or other open textile fabric, and passing up through it a current of air, first cold at the front of the machine, and then gradually be- 35 coming heated toward the other end of the ma- chine sufficiently to evaporate the surplus moisture. The mass of tobacco is meanwhile kept in motion upon the screen by operatives from the head toward the other end of the ma- 40 chine until the proper degree of dryness is ob- tained. It is found in practice that by gradu- ally heating the current of air, as described, the flavor of the tobacco is much improved.

My invention consists in the various opera- 45 tive combinations of the mechanism employed by me.

The construction of an apparatus suitable for the employment of the process used by me will be best understood by reference to the ac- 50 companying drawings, forming a part of this

specification, in which similar letters refer to like parts.

Figure 1 is a vertical longitudinal section, and Fig. 2 is a horizontal section, of my dry- 55 ing-machine, the deflecting-boards not being shown. Fig. 3 is an end elevation, showing the induction and exhaust pipes for steam.

In Fig. 1, A is the hot-air case, closed upon all sides except the top, upon which is placed 60 the tray B, having a bottom of perforated metal, wire-screen, or a netting of textile fabric.

In the case A are located numerous coils of steam-pipe, E E E E, placed as shown, and supported by pieces of iron pipe d d d, Fig. 1. The steam, preferably live steam, is admitted 65 at D D, and the exhaust, with the water of condensation, is passed off through the pipe F.

At one end of the machine is placed a fan-blower, G, which forces cold air into the case A. The mouth-piece a of the blower G is 70 made fan-shaped, as shown at a, Fig. 2, thereby converting the round mouth of the blower into an elongated opening, as seen at a, Fig. 3. By this means the blast of air is spread out so as to cover the whole width of the case. 75

Within the case, and at equal distances, are placed one or more deflecting-boards, as shown at H K L, Fig. 1, regularly increasing in width, whose province it is to break and deflect the current of air as it leaves the mouth-piece a. 80 These boards are placed at an angle, so as to deflect the current of air up between the steam-pipes, whereby it is heated sufficiently for the purpose, being gradually more and more heated as the distance increases from the air-inlet. 85

The tobacco, being placed on the screen C in the tray B near the point M to a depth generally exceeding two inches, but varied as experience will dictate, is gradually turned and moved toward the point N. By this means 90 the tobacco is first placed at the coolest point and gradually heated as it is turned over, and finally removed at the hottest place. As fast as the dried tobacco is moved from M to N and removed a fresh supply is put upon the screen 95 at M. By passing the heated air up through the tobacco the exhalations resulting from the evaporation of the solution in which the tobacco has been immersed pass off in the open air as fast as they are produced, leaving the 100

tobacco soft and pliable, as well as preserving the flavor much better than it is possible to do when it is dried in a tightly-closed box or other receptacle.

5 Having thus described my invention, upon which I wish to secure Letters Patent, I claim—

1. The case A, with the steam-pipes E E, the blower G, tray B, and deflecting-boards H K L, arranged as described, and for the purposes specified.

2. The deflecting-boards H K L, in combination with the blower G and steam-pipes E E, arranged as described, and for the purposes specified.

This specification signed and witnessed this 15
29th day of March, 1880.

LAWRENCE LOTTIER.
